Des. 220,858
Patented June 1, 1971

220,858

SHOE GROOMING STAND

Albert T. Poole, Lakeside, Calif., assignor to White Fields
Inc., West Columbia, S.C.

Filed June 25, 1969, Ser. No. 17,867

Term of patent 14 years

Int. Cl. D28—99

U.S. Cl. D86—12

FIG. 1

FIG. 7

FIG. 4

FIG. 6

FIG. 1 is a perspective view of a shoe grooming stand, showing my new design;

FIG. 2 is a front side view of the stand;

FIG. 3 is a right hand end view of the stand;

FIG. 4 is a cross sectional view taken along line 4—4 of FIG. 3;

FIG. 5 is a left hand end view of the stand;

FIG. 6 is a top plan view of the stand; and

FIG. 7 is a bottom plan view of the stand.

The view of rear side of the article opposite the front side shown in FIG. 2 is a mirror image of FIG. 2.

I claim:

The ornamental design for a shoe grooming stand, as shown and described.
